STOPPING DEVICE FOR BOTTLES AND THE
LIKE POSITIVELY PREVENTING THE FILL-
ING OF THE CONTAINER WITH NEW
LIQUID

Ernesto Cocchi, Milan, Italy

Application May 31, 1951, Serial No. 229,028

Claims priority, application Italy March 24, 1951

9 Claims. (Cl. 215—23)

1

The present invention relates to a stopping device for containers, like bottles and the like, apt to permit the gradual emptying off of the container but not the introduction of a new liquid into said container. This device is of the type in which a shutting off valve, movable inside of a cap fixed to the neck of the bottle, and lockable, by operating a shutting cover external to the cap, onto a seat also fixed to the neck of the bottle, does not open if unlocked, but when the bottle has been inclined downwards of an angle permitting the delivery, but not the introduction, of liquid. The device, according to the invention, shows a particularly original and advantageous structure, apt to ensure, through a very simple and easy operation, a regular working not subject to jamming caused, for instance, by sugary deposits or other similar drawbacks that happen with the known types.

Said device is characterised by this, that the body of the valve has on its face opposed to the one turned towards the seat, a conical projection whose axis coincides with that of the valve, and is apt to engage itself, for guiding the valve, into a corresponding cavity in a pin of the cover, mounted in an unseparatable, but rotatable and slidable way, in a hub integral to the cap, an additional guiding of the valve being ensured by a stem of the valve itself axially projecting from its face facing the seat through a ring centrally carried by said seat.

According to another characteristic of the invention the connection between pin and hub is of the bayonet type so as to accelerate the operation of opening and closing the cover and correspondingly of the locking and unlocking of the valve body, which is provided, all around the conical projection, with a teeth formation with which at first engages the element of the bayonet joint fixed to the hollow pin, in order to impress to the valve a slight rotational movement and to loosen it from the seat to which it might eventually have stuck.

According to a further characteristic of the invention, the valve stem may carry at its free end a float which has the purpose, when necessary, of anticipating the beginning of the delivery of the liquid in respect with the angle of inclination of the bottle.

Further particulars and characteristics of the object of the invention will be made evident by the following description of an example of construction, illustrated in the appended drawings, in which:

Fig. 1 is for one half a longitudinal section of 55 15 diametrically opposed, into which teeth 18

2

the stopping device mounted on a bottle in a position of locked closure of the valve and for the other half an elevational view of said device.

Fig. 2 is a longitudinal section of the device, 5 with the bottle in a horizontal position and with the valve unlocked, but still in a closed position.

Fig. 3 is a longitudinal section of the device, 10 with bottle inclined so as to provoke the opening of the valve for the delivery of the liquid.

Fig. 4 is an elevational view of the detail of the 15 bayonet type connection for locking the cover of the cap and of the valve.

Fig. 5 is a partial plan view of the valve seat.

Fig. 6 is a section on line x—y of Fig. 1 and

15 Fig. 7 is a plan view of the device, one half of it with the cover of the cap in place and the other half without said cover.

On the mouth of the bottle 1 are applied, with 20 the interposition of a washer gasket 2, plate 3 acting as a seat to the valve and cap 4, which are held fast in place by a collar 5 fastened to the neck of the bottle. On seat 3 of the valve is indicated with 6 the delivery opening of the liquid at the center of which is disposed a ring 7 having a 25 central hole 7' fast to the seat. Valve 8, located inside cap 4 is concave in shape and from its side facing the outside axially projects a conical part 9, whilst from the opposite end sticks out a stem 10 going through ring 7 of seat 3, and that in the 30 example of the drawing is provided at its end with a float 11.

Said float is shaped like a double cone, with a 35 taper corresponding to that of conical projection 9. Cap 4 is closed with the interposition of a gasket ring 12, by a cover 13, on the internal face 40 of which is fixed a hollow pin 14. Said pin 14 is unseparably fixed, but is free to turn and slide, in a hub 15 of cap 4, whose flange connection to the cap has openings 16 for the delivery of the liquid and its lower end is so shaped, internally, as to consent the adaptation thereto of projection 9 of valve 8, which rests with its conical surface against a corresponding conical surface of the lower end of hollow pin 14.

Around projection 9 valve 8 is provided with 45 a crown of teeth 17, into two diametrically opposed spaces of which engage, when cover 13 is closed, the ends of two diametrically opposed teeth 18 of pin 14, the other ends of which find a 50 rest on the lower annular surface of hub 15 forming two helicoidal paths. So, in order to open cover 13 it is sufficient to cause it to turn so as to make teeth 18 slide over said helicoidal paths that end in axial blind grooves 19 of hub 55 15 diametrically opposed, into which teeth 18

Fig. 1 is for one half a longitudinal section of 55 15 diametrically opposed, into which teeth 18

are caused to penetrate, thus permitting of getting cover 13 away from valve 8 and to free the latter. Under these conditions valve 8 can slide on its seat 3, when bottle 1 (Fig. 2) is caused to be inclined, and displace itself axially keeping parallel with its axis to the axis of the bottle when the inclination of the bottle is carried under a horizontal plane (Fig. 3), by means of the double guide provided by the engagement of projection 9 with the cavity of pin 14 and of float 11 with ring 7. Only then the liquid contained in the bottle can flow out. Cover 13 has its peripheral edge knurled in order that it may be rotated easily and under the knurled part 20 of the edge it has a tongue 21 soldered onto cap 4 so that cover and cap are fastened together when, after filling the bottle, the stopping device described is applied thereon. On the upper part of said tongue, between it and the cap, a small passage may be left for a wire 22 permitting the application of a guarantee seal. Said tongue is of very little strength and may very easily be broken by rotating cover 13 in respect with the cap when beginning to use the bottle. The working of the device appears clearly from the drawing as it has been explained.

As may be gathered from the drawings, the valve 8 has a recess 8' facing the seat 3. Therefore, if a person should intend to refill the bottle 1 in an unauthorized manner when the bottle is in the tilted position shown in Fig. 3, the valve 8 would float on the liquid poured into the stopping device and would automatically engage its seat 3. Thus, the bottle is automatically sealed and an unauthorized refilling of the bottle is rendered impossible.

It is understood that the constructional details may be varied within very wide limits in comparison with those represented in the drawings and above described, the device still remaining at all times within the scope of the invention.

What I claim is:

1. A dispensing closure for a receptacle having a neck, comprising in combination: a casing capable of attachment to the neck of the receptacle outside the mouth thereof, a valve seat arranged in said casing at the bottom end thereof facing the mouth of the neck, said valve seat having apertures for the passage of liquid from the receptacle into the casing and having a center bore, a valve movably arranged within said casing and capable of sealing engagement with said seat, the top wall of said casing having apertures for the delivery of the liquid and having a center bore, a cover structure including a cover and a stud fixed to each other, said stud being rotatably and axially displaceably mounted in the center bore of said top wall whereby said cover may be shifted between a closing position in contact with said top wall and an opening position spaced from said top wall, said stud having a recess facing said valve, a protrusion arranged on the valve at its side facing said recess for engagement with the latter, a stem on the opposite side of said valve passing through the center bore of said valve seat, said protrusion in cooperation with said recess and said stem in cooperation with said last mentioned center bore being arranged for guiding said valve during movements thereof, and coupling means including first and second engaging means arranged on said cover structure and on said valve, said first and second engaging means being in positive engagement with each other when said cover is in its closing position whereby the valve may be ro-

tated relative to its seat upon a rotation of the cover and being movable relative to each other after such a rotation of the cover when the latter is axially displaced.

5. In a dispensing closure as claimed in claim 1, said top wall including a hub provided with said center bore, and a pin and slot connection between said hub and said cover structure limiting an axial displacement of said cover structure 10 relative to said hub to a predetermined angular position between the cover structure and the hub.

3. In a dispensing closure as claimed in claim 1, said top wall including a hub provided with 15 said center bore, said cover structure being rotatable relative to said hub between a locking position and a releasing position, first means on said hub cooperating with said cover structure for urging the latter against said valve when said cover structure is in its locking position so as to tighten said valve on its seat, and second means on said hub cooperating with said cover structure for guiding an axial displacement thereof when said cover structure is in its releasing position.

4. In a dispensing closure as claimed in claim 1, a float arranged at the free end of said stem.

5. In a dispensing closure as claimed in claim 1, said recess of the stud and said protrusion on the valve being of conical shape.

6. In a dispensing closure as claimed in claim 1, said valve having a recess facing said seat.

7. A dispensing closure for a receptacle having a neck, comprising in combination: a casing capable of attachment to the neck of the receptacle outside the mouth thereof, a valve seat arranged in said casing at the bottom end thereof facing the mouth of the neck, said valve seat having apertures for the passage of liquid from the receptacle into the casing and having a center bore, a valve movably arranged within said casing and capable of sealing engagement with said seat, a hub provided with a center bore arranged on the top wall of said casing, said top wall having a plurality of apertures for the delivery of the liquid arranged around said hub, a cover, a stud fixed to said cover, said stud being rotatably and axially displaceably mounted in the center bore of the hub of the top wall whereby said cover may be rotated between a locking position and a releasing position and may be axially displaced between a closing position in contact with said top wall and an opening position spaced from said top wall, said stud having a recess facing said valve, a protrusion arranged on the valve at its side facing said recess for engagement with the latter, a stem on the opposite side of said valve passing through the center bore of said valve seat, said protrusion in cooperation with said recess and said stem in cooperation with said last mentioned center bore being arranged for guiding said valve during movements thereof, a set of coupling teeth arranged on said valve around said protrusion, and a bayonet-type connection, including cooperating elements, arranged between said hub and said stud, one of the elements of said bayonet-type connection being rigid with said stud and being in positive engagement with said coupling teeth for causing a rotation of said valve relative to its seat upon a rotation of said cover and being movable relative to said coupling teeth after such a rotation of the cover when the latter is axially displaced.

8. A dispensing closure for a receptacle having a neck, comprising in combination: a casing

capable of attachment to the neck of the receptacle outside the mouth thereof, a valve seat arranged in said casing at the bottom end thereof facing the mouth of the neck, said valve seat having apertures for the passage of liquid from the receptacle into the casing and having a center bore, a valve movably arranged within said casing and capable of sealing engagement with said seat, a hub provided with a center bore arranged on the top wall of said casing, said top wall having a plurality of apertures for the delivery of the liquid arranged around said hub, a cover, a stud fixed to said cover, said stud being rotatably and axially displaceably mounted in the center bore of the hub of the top wall whereby said cover may be rotated between a locking position and a releasing position and may be axially displaced between a closing position in contact with said top wall and an opening position spaced from said top wall, said stud having a recess facing said valve, a protrusion arranged on the valve at its side facing said recess for engagement with the latter, a stem on the opposite side of said valve passing through the center bore of said valve seat, said protrusion in cooperation with said recess and said stem in cooperation with said last mentioned center bore being arranged for guiding said valve during movements thereof, said hub having a pair of diametrically opposite arranged recesses extending substantially in the direction of its longitudinal axis and having a pair of helically arranged lower edges each merging into one of said recesses, a pair of diametri-

cally opposite coupling lugs arranged on the outside of said stud, and a set of coupling teeth arranged on said valve around said protrusion, said coupling lugs being capable of operative engagement with said set of coupling teeth when said cover is in its closing position whereby the valve may be rotated relative to its seat upon a rotation of said cover, said coupling lugs coming into operative engagement with said helical edges of the hub during a rotation of the cover from its releasing position into its locking position whereby said lugs are urged against said valve for tightening same on its seat, and said coupling lugs are in register with said recesses of the hub when the cover is in its releasing position so that said lugs may enter said recesses during an axial displacement of the cover into its opening position.

9. In a dispensing closure as claimed in claim 8, a float arranged at the free end of said stem.
